UNITED STATES PATENT OFFICE.

JOSEPH L. WRIGHT, OF WASHINGTON, DISTRICT OF COLUMBIA, ASSIGNOR, BY MESNE ASSIGNMENTS, TO THE NORTH ELECTRIC COMPANY, OF CLEVELAND, OHIO, A CORPORATION OF OHIO.

TELEPHONE-EXCHANGE SYSTEM.

1,027,392.

Specification of Letters Patent. Patented May 21, 1912.

Application filed January 8, 1907. Serial No. 350,657.

To all whom it may concern:

Be it known that I, JOSEPH L. WRIGHT, a citizen of the United States, residing at Washington, in the District of Columbia, have invented certain new and useful Improvements in Telephone-Exchange Systems, of which the following is a specification, reference being had therein to the accompanying drawing.

10 This invention relates to telephone exchange systems, and especially to those systems which employ automatic switching apparatus for effecting connection between subscribers.

15 The object of the invention is to provide means whereby a calling subscriber whose station is located on a party line, may be connected so as to converse with another party on his own line.

20 In all automatic systems provision is made for guarding lines already in use from interruption, some change in condition of the circuits being relied upon to affect an electromagnet in the testing connector switch, thus giving the equivalent of the operator's test in the ordinary manual system. Such a test must extend to lines which are calling as well as lines which are called, since a line calling is of course busy for the time being.

25 From this it results that if the line calling is also the line called, then it will find itself busy and be unable to complete the connection with itself unless special provision be made for a reverting busy test. I make such provision by balancing potentials on the test relay when testing back on the calling line only.

30 In the present case a metallic circuit system will be illustrated and described, in which a ground is placed on the tip side of the line or the first trunk during use, and the test is made for this ground. If it is found, the line is busy, otherwise not. In testing, a relay is connected from the test terminal to battery, and in order to accomplish my present purposes, I provide that when this test terminal is applied to the sleeve side of the calling end of the switching circuit in any particular case, battery is momentarily connected also on the tip side of the answering end of the same. The effect of this is to balance potentials on the terminals of the test relay or magnet for the same circuit and for no other. Since this special condition only lasts an instant, the chance

of thereby letting another party get in upon the same connection is infinitesimal.

It is obvious that the present invention may be applied to semi-automatic as well as to full automatic systems. The switching equipment of such systems is substantially the same in principle and arrangement and the busy test would therefore be the same. In fact, in any case in which an automatic connector switch is employed for making the final selection of the line wanted, the present invention is applicable.

My invention is illustrated in the accompanying drawings wherein—

Figure 1 shows two subscribers' stations and a portion of the central office equipment. Fig. 2 shows a first and second selector switch and a connector switch of the well known Strowger type.

Referring now to Fig. 1, the two subscribers' stations A and A' are equipped with apparatus usual in common battery systems. As the apparatus at each station is identical it will only be necessary to describe that of one. Referring to station A the equipment consists of the transmitter T, receiver R, hook H, ringers Q, and condenser C. In addition to these I provide a sending device which is represented diagrammatically by the push button O which contains two normally closed contact springs o and o'. The subscriber desiring to send a number sets up his sending machine which when running down makes and breaks the contact springs o and o'.

The line-wires 2 and 3 from the subscribers' stations terminate in the central office on a relay S and retardation coil I. The relay S controls a pair of solenoids A and B, although sluggish relays could be used instead. The solenoid B is connected to the front contact s' by the wire 24 and to ground by the wire 29. The solenoid A is connected to the contact s⁴ and to ground by the wire 29. The contacts s⁴, s² and s³ are normally connected and when the relay S is energized and closes the circuit of the solenoid B, battery is placed on the contact s² by the following path: battery B, 22, 30, b', 23, s². The solenoid B keeps the core b⁵ drawn up when the contacts s' and s of the relay S are closed and also while the relay S makes and breaks its contacts during the transmission of the impulses from the subscriber's station. In other words the core of the solenoid B will only drop down

75 80 85 90 95 100 105 110

when the contacts s' and s of the relay S are open.

The contacts s⁴ and s² are connected in series with the retardation coil I and the contacts s⁴ and s³ are connected in series with the solenoid A.

The contacts s⁴ and s² are connected in series with the retardation coil I and the contacts s⁴ and s³ are connected in series with the solenoid A.

to its normal position after the contacts s and s' remain broken for quite a while as would be the case when a subscriber hangs up his telephone at the end of a conversation. While this solenoid is active battery is connected to the contact s^2 of the relay S and rapidly makes and breaks between it and the contact s^4 will in turn keep the solenoid A active allowing the core a^5 to remain drawn up so long as impulses are being transmitted. Between every set of impulses there is a long make or pause caused by the subscriber setting up his sending device for transmitting another set of impulses. During this interval the solenoid A is deenergized and its core a^5 drops down to its normal position. At the end of the conversation the relay S becoming deenergized closes the contacts s^2 and s^4 causing the solenoid A to become active but at the same time the circuit of the solenoid B is broken at the contacts s and s' and the core b^6 thereupon drops, opening the springs b and b' disconnecting battery from the contact s^2 and deenergizing the solenoid A whose core a^5 thereupon drops. It will be seen from the foregoing description of these two solenoids that the core of the solenoid A drops between every group or set of impulses and that the core of the solenoid B only drops at the end of a conversation. With this combination I am enabled to use the solenoid A for sending a rotary or switching impulse after each set of signals so as to work the side switches in the selector and connector switches. The solenoid B is used for releasing various switches. When the core of this solenoid drops down battery is placed simultaneously on the wires 4 and 5 by the closure of the springs b^2 , b^3 and b^4 . Battery is afterward disconnected from the wires 4 and 5 by the core a^5 of the solenoid A dropping and opening the contacts a^3 and a^4 . Bridged battery is connected between the windings of the relay S and retardation coil I for supplying talking battery to the calling subscriber. The condensers C^2 and C' are inserted in the wires 3-4 and 2-5 respectively to prevent battery flowing to the various switches.

When the core of the solenoid A drops down between each group of impulses in addition to connecting battery momentarily to number 5 side of the trunk it also connects battery to number 3 side of the line and from there by wire 40 to multiple contacts in the connector switch. Battery is placed on the tip side of line in this manner so as to disable the busy test when a party calls for someone on his own line, otherwise his own line would test busy.

Referring now to Fig. 2, I have shown circuits of a first selector, second selector and connector switches as described in Letters Patent 815,321 and 815,176 granted March

13, 1906 to Keith and Erickson. I will not attempt to describe these circuits in detail. The first selector switch G consists of the vertical relay V which when energized closes the circuit of the vertical magnet X which in turn causes the spindle Z carrying the wipers to step up vertically. The rotary relay V' when energized operates the private relay U causing the side switches to make one step. The rotary magnet X' has its circuit closed after the side switches have made one movement and will continue to vibrate causing the spindle Z to rotate until the test wiper z finds a contact free from ground. As soon as this happens the side switches make still another movement disconnecting the vertical and rotary relays from the trunk wires and close the trunk wires themselves through to the trunk wipers. The last movement of the side switches also connects the trunk release relay J to the test wiper z . The magnet J' is the release magnet and when operated restores the switch to its normal position. The circuits of the second selector switch G' are similar to those of the first selector switch and need not be described. Referring now to the connector switch G^2 , the circuits shown are the same as in the Letters Patent before referred to, with the exception of the release mechanism. In the present case a release relay J^4 is used, which when actuated closes the circuit of the release magnet J^5 . Instead of testing on a third or test wiper I do the testing directly on the rotary or sleeve side of the line. In place of the ordinary back release relays which are connected to the trunk wires 14 and 15 respectively, I have replaced them with the retardation coils I^2 and I^3 with bridged battery between them for supplying current to the called subscriber. In this particular case I have shown the contacts in the connector switch connected directly to the calling line as I wish to illustrate and show the method of calling back on your own line. The changes I have made in this circuit do not affect the operation of this switch in the slightest. The vertical relay V^4 , rotary relay V^5 , private relay U^2 and the ringing relay Y , remain unchanged and the method of releasing is the same.

The operation of this system is as follows: Referring to Fig. 1, the subscriber at station A desiring to be connected with station A' on the same line first removes his telephone which closes the line circuit, energizes the relay S which in turn closes the circuit of the solenoid B . The core of the solenoid B now being drawn up battery is connected to the contact s^2 of the relay S by the following path: battery B , 22, 30, b' , 23, s^2 . The relay S at this time being energized keeps the circuit of the solenoid A open. The subscriber at station A after removing his telephone sets up his sending device to

the desired number and this in running down makes and breaks the contacts o and o' according to the number of impulses to be sent. These makes and breaks operate the relay S at the central office which in turn makes and breaks its own contacts. The making and breaking of the contacts s^2 and s^4 cause the solenoid A to become energized and draw up the core a^5 . The making and breaking of the contacts s and s' keep the solenoid B energized, while the making and breaking of the contacts s^2 and s^3 send impulses over the trunk wire number 4 to the first selector switch. These impulses of course, correspond to the makes and breaks of the contacts o and o' . After this first set of impulses there is a momentary closure of the line due to the subscriber setting his sending device for another set of impulses. During this time the relay S remains energized and the core a^5 of the solenoid A drops down and in doing so momentarily closes together the contact springs a , a' and a'' . This closure places battery on the trunk wire 5 and on the line wire 3. Battery being thus momentarily placed on the trunk wire 5 operates the rotary relay in the first selector switch, while battery being placed on line wire number 3 disables the busy test relay in the connector switch as will be described later.

Referring now to Fig. 2, the first set of impulses coming over number 4 side of the trunk operates the relay V which in turn closes the circuit of the magnet X which causes the spindle Z to step up vertically and bring the wipers opposite a row of contacts leading to the proper group of second selector switches. After the first set of impulses the solenoid A becomes de-energized and its core dropping down places battery on number 5 side of the trunk by the following path: battery B , 22, s , s' , 28, a^2 , a' , 27, 5. This impulse operates the relay V' which in turn closes the circuit of the private relay U causing the side switch to make one movement cutting on the rotary magnet X' which causes the spindle to rotate until the test wiper finds the contact leading to an idle second selector switch. When such a switch is found the side switch makes one more movement cutting off the vertical and rotary relays and connects the trunk wires 4 and 5 to the trunk wipers which rest upon contacts leading to the second selector switch. The subscriber now being connected to the second selector switch sends in the second set of impulses which now operate the second selector switch G' in the same manner that the first set of impulses operated the first selector switch. The subscriber now being connected to a connector switch containing multiples of the desired line sends in the third set of impulses. This set of impulses coming in operates the relay V^4 which in turn closes the circuit of the magnet X^4 which in turn causes the spindle Z^2 to step up vertically and bring the wipers opposite a row containing the contacts leading to the desired line. The rotary impulse now coming in operates the relay V^5 causing the side switch to make one movement, disconnecting the magnet X^4 and in its place connecting the magnet X^5 , it also connects the test relay J^4 to the sleeve side of the line through the normally open contacts u and u' of the relay U^2 . The fourth set of impulses now coming in operate the relay V^4 which now closes the circuit of the magnet X^5 which in turn causes the spindle to rotate and bring the wipers to rest upon contacts leading to the desired line. In this case, the desired line happens to be your own line as the party wanted is connected to the same pair of line wires. The last rotary impulse now coming in closes the circuit of the relay V^5 which in turn closes the circuit of the relay U^2 connecting the test relay J^4 to the sleeve or number 19 side of the trunk. At the same time that this relay is connected to the sleeve side of the trunk, battery is placed on the tip side of line and as the tip side of the line in this case is connected to the sleeve side of the trunk it is impossible for the test relay to operate as it is connected to battery itself. The above condition can only be brought about when trying to signal back on the line which initiates the call. If calling for another line and that line happens to be busy, ground would be connected to the tip side of the trunk through the battery supply relay and that line would test busy and the relay J^4 would become energized and close the circuit of the magnet J^5 restoring the switch to its normal position. The subscriber now being connected to his own line sets up his sending device so as to send in a set of ringing impulses. These impulses now coming in operate the relay V^4 which in turn closes the circuit of the ringing relay Y which became connected when the last rotary or test impulse was sent in, causing the side switch to make one more movement. These ringing impulses operating the relay Y place generator current on the called line ringing the bell of the desired party who upon removing his telephone is enabled to talk with the party on the same line.

At the end of the conversation the calling subscriber upon hanging up his telephone effects the release of the various switches in the following manner: During conversation the core of the solenoid B remains drawn up while that of the solenoid A remains down. When the calling subscriber hangs up his telephone the relay S becomes de-energized whereupon the solenoid A at once

draws up its core a^5 while the core b^5 of the solenoid B begins to drop and as soon as it assumes its normal position battery is connected to both sides of the trunk by the following path: battery B, a^4 , a^3 , b^4 , b^3 , b^2 , 21, 31. After it has assumed its normal position the contacts b and b' are broken, opening circuit of the solenoid A whose core a^5 thereupon begins to drop and as soon as it assumes its normal position the contacts a^3 and a^4 are broken and battery is removed from the trunk wires 4 and 5 respectively. It will be seen from this method of operation that the joint action of these 15 solenoids at the end of the conversation places battery momentarily on both sides of the trunk for releasing. These momentary impulses close the circuit of the relay V^4 and the relay V^5 at the same time, thus closing the circuit of the relay J^4 which in turn closes the circuit of the magnet J^5 restoring the connector switch to its normal position. The circuit of the relay J^2 in the second 20 selector switch was closed in series with that of J^4 and upon operating closes the circuit of the magnet J^3 restoring the second selector switch to its normal position. In the first selector switch the relay J has its 25 circuit closed in series with the magnet J^3 and becoming energized closes the circuit of the magnet J' restoring the first selector switch to its normal position. All the apparatus is now returned to its normal or starting 30 position and ready to be used for another call.

Having thus described my invention what I claim and desire to secure by Letters Patent is:

1. In a telephone exchange system a plurality of subscribers' lines and automatic switching apparatus for interconnecting them; means in the switching apparatus for testing a subscriber's line, and other means simultaneously operated to produce a balance of potentials on the first means in case the line tested is also the line calling, but not otherwise, substantially as described.

2. In a telephone exchange system a plurality of subscribers' lines and automatic switches for interconnecting them, an electromagnet brought into use when completing a connection, for the purpose of testing the line wanted to ascertain if it is busy, means to produce a difference in potential 55 between the testing terminal of each line and the testing terminal of said magnet when the line becomes busy, and means associated with the switches for balancing said difference of potential in case the line calling is

also the line called, but not otherwise, substantially as described.

3. In a telephone exchange system, a plurality of subscribers' lines and automatic switches for interconnecting them, answering and calling terminal connections for the lines, means for changing the potential condition on the calling terminal of a line when it becomes busy, a test relay associated with a connector switch, and means for changing the potential on the answering terminal connection of the calling line each time the test relay is energized, whereby a balance of potentials is produced across the terminals of said relay when the line calling is also the line called, substantially as described.

4. In a telephone exchange system a plurality of subscribers' lines and automatic switches for interconnecting them, answering and calling multiple terminal connections for each line, means for initiating a connection through the answering terminal connections and one or more automatic switches to the calling terminal of the line wanted, means for grounding a line terminal when the line becomes busy, a test relay associated with a connector switch and connected from a test terminal to battery, and means for simultaneously applying said relay to the calling terminal of the wanted line and at the same time connecting battery to the corresponding answering terminal of the calling line, whereby a balance of potentials is produced on the relay if the calling and called lines are the same, substantially as described.

5. Apparatus for testing telephone or signaling terminals comprising (1) means adapted when a terminal is idle to maintain a predetermined potential thereon; (2) means becoming active when the line of the terminal is calling or called, to change the potential thereon; (3) means acting when the line is both calling and called to neutralize or balance the change in potential; and (4) means adapted to be brought into conjunction with a line terminal for testing purposes, said means being responsive to the changed potential when the line is calling or called, but remaining irresponsible when the line is both calling and called.

In testimony whereof I affix my signature in presence of two witnesses.
